[57] **CLAIM**

The ornamental design for a self-adhering, anti-compressive wound covering shield, as shown and described.

DESCRIPTION

FIG. 1 is a top perspective view of a self-adhering, anti-compressive wound covering shield showing our new design;

FIG. 2 is a top plan view thereof;

FIG. 3 is a bottom plan view thereof;

FIG. 4 is a front elevational view thereof;

FIG. 5 is a rear elevational view thereof; and,
FIG. 6 is a side elevational view thereof, this view being a mirror image of the opposite side elevational view.
